UNITED STATES PATENT OFFICE.

EMANUEL J. GRACE, OF ERIE, PENNSYLVANIA.

EXPLOSIVE-ENGINE STARTER.

No. 800,290.

Specification of Letters Patent.

Patented Sept. 26, 1905.

Application filed May 2, 1904. Serial No. 205,940.

To all whom it may concern:

Be it known that I, EMANUEL J. GRACE, a citizen of the United States, residing at Erie, in the county of Erie and State of Pennsylvania, have invented new and useful Improvements in Devices for Preventing Back-Firing Action in Explosive-Engine Starters, of which the following is a specification.

This invention relates to devices for preventing back-firing action in explosive-engine starters; and it consists in certain improvements in the construction thereof, as will be hereinafter fully described, and pointed out in the claims.

15 The object of the invention is to provide a device which will prevent the back-turning of the starting-lever, whatever its form may be, usually a crank, when an explosion takes place in the engine, so as to force the starting-lever backward. Where this occurs, the operator starting the engine is liable to be seriously injured by reason of the great force by which the lever is thrown back. My device prevents this backward movement of the 25 starting-lever.

The invention is illustrated in the accompanying drawings, as follows:

Figure 1 shows a section on the line 1 1 in Fig. 2; Fig. 2, a section on the line 2 2 in 30 Fig. 1; Fig. 3, an end view of the device, a part being removed to show spring construction, the view being from the left of Fig. 2. Fig. 4 is an end view of the device from the right of Fig. 2; Fig. 5, a side elevation, partly in 35 section, showing an alternative construction.

A marks a bracket through which the crank-shaft B passes. It has the journal-lug a, in which the shaft part C is journaled, the collar I preventing the movement of the shaft part 40 endwise in one direction. A sleeve or shaft part C is fixed on the shaft by the key b. This may be an enlargement of the shaft itself, but ordinarily would be a separate sleeve, as shown. The sleeve has key-recesses c in it, 45 in which the keys D seat. The keys D are preferably in the form of rollers, as shown in Fig. 2, but may be in the form of balls D', as shown in Fig. 5, this being the only difference between the construction in Fig. 1 and 50 the alternative construction in Fig. 5. The keys may be other shapes than round, but are preferably round. The keys are carried in pockets e in a key-sleeve E. The crank or starting lever F is fixed with the sleeve E. 55 A retaining-sleeve G is arranged around the key-sleeve E and normally holds the keys so

that the inner surface of the keys protrude into the recesses c, or, in other words, are seated therein so that the key-sleeve E and shaft part C are normally locked together 60 with a forward movement of the crank-lever. A ratchet-wheel H is journaled on the extension g of the retaining-sleeve G. It is arranged between the friction-washers h, on which pressure is exerted by the nut h'. A 65 pawl J operates on this ratchet-wheel to lock it against turning backward. The pawl J is mounted on a pin j. This pin is screwed into the lug a' on the bracket. The crank may be turned backward against the friction 70 to get it in proper position to start the engine, as is ordinarily the case.

The retaining-sleeve G has a limited movement on the key-sleeve E, as shown in Fig. 1. This movement is limited by a screw e', which 75 is fastened in the key-sleeve and protrudes through the opening g' in the retaining-sleeve. A screw-plate g'' is preferably provided for covering the opening.

The retaining-sleeve is provided with a recess g''. (See Fig. 1.) This recess is so positioned relatively to the pocket e that the key D may be brought into register with this recess by a relative movement of the retaining-sleeve and key-sleeve within the limits of the 80 stop provided by the screw e'. The springs K are arranged in the annular recess g''' in the ends of the retaining-sleeve. A cover-plate k is preferably arranged over the springs. This plate is removed in Fig. 3 to better show construction. One end of the spring abuts the pin k' on the key-sleeve and the other end abuts the pin k'' on the retaining-sleeve. The spring is tensioned to keep the parts normally 85 in the position shown in Fig. 1—that is, with the key G out of register with the recess g''. When in this position, the keys D are seated in the recess c, so that with a forward movement of the starting-lever F the shaft B is 90 moved with it, so as to start the engine. 95

100 Where back-firing takes place, so that the shaft B is turned backward, the ratchet mechanism comprising the ratchet H and pawl J prevents the return movement of the retaining-sleeve G, so that the key-sleeve E is moved 105 backward relatively to the retaining-sleeve against the tension of the springs K. When the pocket e in the key-sleeve is brought into register with the recess g'', the pins D move 110 into these recesses g''', and this carries them out of the recess c, so that the shaft B, with the shaft part C, may continue the backward move-

ment without carrying with it the starting-lever F, thus preventing the injurious effects ordinarily encountered with back-firing in this manner of devices.

5. What I claim as new is—

1. In a device for preventing back-firing action in explosive-engine starters, the combination with the engine-shaft and starting-lever; of a clutch mechanism comprising a key-sleeve connected with the starting-lever and having a key-pocket therein; a key in said pocket; a retaining-sleeve adapted to normally hold said key in a position protruding from the opposite surface of the key-sleeve, and being provided with a recess into which said key may move when a backward movement of the shaft occurs; and a shaft part having a recess into which said key is normally forced by the retaining-sleeve.
2. In a device for preventing back-firing action in explosive-engine starters, the combination with the engine-shaft and starting-lever; of a clutch mechanism comprising a key-sleeve connected with the starting-lever and having a key-pocket therein; a key in said pocket; a retaining-sleeve adapted to normally hold said key in a position protruding from the opposite surface of the key-sleeve, and being provided with a recess into which said key may move when a backward movement of the shaft occurs; a shaft part having a recess into which said key is normally forced by the retaining-sleeve; and a spring between the retaining and key sleeve arranged to normally hold the sleeve in position to lock the key in the recess in the shaft part and the recess in the retaining-sleeve out of register with the key-pocket.
3. In a device for preventing back-firing action in explosive-engine starters, the combination with the engine-shaft and starting-lever; of a clutch mechanism comprising a key-sleeve connected with the starting-lever and having a key-pocket therein; a roller-key in said pocket; a retaining-sleeve adapted to normally hold said key in a position protruding from the opposite surface of the key-sleeve, and being provided with a recess into which said key may move when a backward movement of the shaft occurs; and a shaft part having a recess into which said key is normally forced by the retaining-sleeve.
4. In a device for preventing back-firing action in explosive-engine starters, the combination with the engine-shaft and starting-

lever; of a clutch mechanism comprising a key-sleeve connected with the starting-lever and having a key-pocket therein; a key in said pocket; a retaining-sleeve adapted to normally hold said key in a position protruding from the opposite surface of the key-sleeve, and being provided with a recess into which said key may move when a backward movement of the shaft occurs; a shaft part having a recess into which said key is normally forced by the retaining-sleeve; and a ratchet mechanism for locking the parts against back-turning.

5. In a device for preventing back-firing action in explosive-engine starters, the combination with the engine-shaft and starting-lever; of a clutch mechanism comprising a key-sleeve connected with the starting-lever and having a key-pocket therein; a key in said pocket; a retaining-sleeve adapted to normally hold said key in a position protruding from the opposite surface of the key-sleeve, and being provided with a recess into which said key may move when a backward movement of the shaft occurs; a shaft part having a recess into which said key is normally forced by the retaining-sleeve; and a frictionally-held ratchet mechanism for locking the parts against back-turning.

6. In a device for preventing back-firing action in explosive-engine starters, the combination with the shaft part C having the key-recesses c therein; the key-sleeve E connected with the starting-lever arranged thereon and having the key-pockets e therein, extending through the sleeve and adapted to be brought into register with the recesses c; the keys D arranged in said pockets; the retaining-sleeve G arranged on the sleeve E, said sleeve being adapted to normally hold the keys in the recesses c, but being provided with the recesses g⁴ adapted to be brought into register with the pockets to permit the movement of the keys D out of the recesses c; a ratchet for locking the sleeve G against back-turning; a spring for holding the recess g⁴ in the retaining-sleeve G normally out of register with the pockets e.

In testimony whereof I have hereunto set my hand in the presence of two subscribing witnesses.
